The ornamental design for a tape dispenser, as shown and described.

DESCRIPTION

FIG. 1 is a top, front, left side, isometric perspective view of a tape dispenser in accordance with our design;
 FIG. 2 is a front elevation view thereof;

FIG. 3 is a rear elevation view thereof;

FIG. 4 is a right side elevation view of the tape dispenser in use; a left side elevation view of the tape dispenser being a mirror image of the right side elevation view;

FIG. 5 is a top plan view of the tape dispenser;

FIG. 6 is a bottom plan view thereof; and,

FIG. 7 is a longitudinal cross-section of the tape dispenser looking in the direction of line 7-7 of FIG. 5.

The broken lines shown in the drawings represent environmental subject matter and portions of the tape dispenser that form no part of the claimed design.
